UNITED STATES PATENT OFFICE.

EINAR G. HALLQUIST, OF EDWARDSVILLE, ILLINOIS, ASSIGNOR TO COMMONWEALTH STEEL COMPANY, OF ST. LOUIS, MISSOURI, A CORPORATION OF NEW JERSEY.

CAR PLATFORM.

Application filed July 25, 1925. Serial No. 46,153.

My invention relates to railway rolling stock and consists in an improved construction of the frames of car platforms and the like.

5 The object of my invention is to provide in such a platform a side bearing arch adapted for the application of anti-friction side bearings at a higher level than has been possible with side bearing arches used here-
10 tofore.

It is customary to provide in a car platform spaced transoms and longitudinal members overlying the car wheels, which members have usually been I-shaped or U-shaped in cross section, and it has been customary to apply body side bearings to the bottom flanges of these arches. With some types of truck bolsters, such an arrangement is practical, but in some instances there is 20 insufficient space between the bottom of the platform side bearing arch and the top of the truck bolster beneath the side bearing arch for the application of side bearings, particularly side bearings of an anti-friction 25 type. This condition exists in six wheel trucks in which the side bearings are usually located above the middle wheels of the truck.

I accommodate this condition by so shaping 30 the side bearing arch that it may have a side bearing applied thereto with a substantial portion of the side bearing located above the bottom of the arch. I also so shape the side bearing receiving portion of the arch so 35 that the side bearing may be visible from the side of the car, thereby facilitating inspection of the side bearing.

In the accompanying drawings which 40 illustrate a selected embodiment of my invention—

Figure 1 is a top view of a car platform having my improved side bearing arch.

Figure 2 is a transverse vertical section on line 2—2 of Figure 1 and showing an 45 anti-friction side bearing in position and also showing the adjacent portions of the car truck.

Figure 3 is a side elevation of a portion of the side bearing arch with a side bearing 50 applied and indicating the adjacent wheel.

The platform includes the usual draft 55 sills 1, end sill 2, side sills 3, transoms 4, and center sill connection 5. Connecting transoms 4 on each side of the center line of the car is a longitudinal side bearing arch

member 6, the end portions of which are I-shaped in cross section and in the intermediate portion of which, the web 7 of the I-shaped section is offset, as indicated at 8. The lower flange 9 on one side of the web 60 is also offset as indicated at 10 and the lower flange 11 on the other side of the web is cut away abreast of the offset portion of the web. The upper flange of the arch is disposed the same throughout its length. 65

The offsetting of the member intermediate its ends as described above provides a Z-section with closed ends forming a housing for receiving a side bearing S which may be secured to the underside of the top flange 70 of the arch member by bolts or rivets in the usual manner.

75 Preferably, all of the platform parts are formed from a one-piece casting and the draft sills, end sills, transoms, and side bearing arch are in substantially the same horizontal plane. By means of my arrangement of the side bearing arch, it is possible to mount the side bearing in substantially the same plane without materially decreasing the 80 cross sectional area of the arch member or unfavorably reducing its strength for the vertical loads applied thereto.

In Figure 2 I illustrate the middle wheel 85 12 of a six wheel truck, the truck frame being indicated at 13 and the truck bolster at 14, the latter having integral upwardly and outwardly extending side bearings 15 adapted to cooperate with the body side bearing. It will be obvious from Figure 2 that the 90 outwardly and downwardly opening side bearing housing renders the side bearing visible from the side of the car so that the condition of the side bearing may be easily observed at all times. 95

While I have shown a particular type of side bearing applied to the arch, it will be understood that other side bearings may be applied and the contour of the arch at the point of application of the side bearing may 100 be modified accordingly.

Obviously, the integral structure of all the platform parts shown and described by me is not essential to the embodiment of my invention, and I contemplate the exclusive 105 use of the arch described whether embodied in the integral structure or in a built-up structure. I contemplate such other modifications of my invention as may be included 110 in the scope of my claims.

I claim:

1. In a car platform, transverse transoms spaced from each other, a longitudinal side bearing arch extending between said transoms, there being a side bearing housing formed in said arch above the bottom thereof and opening downwardly.
2. In a car platform, a side bearing arch, and a side bearing housing formed in said arch above the bottom thereof and opening outwardly to permit inspection of the side bearing from the side of the car.
3. In a car platform, transverse transoms spaced from each other, a side bearing arch extending between said transoms and comprising a vertical web and an upper horizontal flange adapted to mount a side bearing which may be applied to the arch or removed therefrom in a substantially horizontal direction.
4. In a car platform, transoms, a side bearing arch between said transoms, all of substantial depth throughout their lengths for sustaining loads applied thereto, and a side bearing housing formed in said arch above the bottom thereof and opening downwardly and outwardly.
5. In combination, a six wheel car truck including a bolster with a side bearing located over one of the middle truck wheels, a car platform mounted on said truck and including transverse transoms spaced longitudinally of the truck from the center line of the center axle, said platform including a longitudinally extending side bearing arch connecting said transoms and substantially level with the body of the platform, and an anti-friction bearing carried by said arch at substantially the same level as the body of said platform and removable therefrom without disassembly of said truck and platform.
6. In a car platform, a side bearing arch I-shaped in cross section at its ends and having a portion of its web and one lower flange offset intermediate its ends and having its other lower flange cut away abreast of said offset portion.
7. In a car platform, transoms, and a transom connecting arch of I-shaped section at its ends and of Z-shaped section intermediate its ends.
8. A one-piece casting comprising a car platform having transoms, and a transom connecting member of I-shaped section at its ends and of Z-shaped section intermediate its ends.

In testimony whereof I hereunto affix my signature this 21st day of July, 1925.

EINAR G. HALLQUIST.
